EXHAUST DEFLECTOR

Linus E. Russell, Springfield, Ohio, assignor to
 Peters & Russell, Inc., Springfield, Ohio, a corporation of Ohio

Application July 21, 1948, Serial No. 39,955

2 Claims. (CL 138—46.5)

1

This invention relates to exhaust deflectors of the kind mounted as extensions upon the tail pipes of automobiles, and more particularly to extensions of the jet or Venturi type.

Devices of this class have a multi-fold function or purpose. They deflect the hot gases of combustion away from the chrome finished and painted surfaces of the automobile and ornament the appearance of the car. Units of the present type also materially aid in exhausting the gases from the tail pipe.

Exhaust deflectors are the subject of considerable experimental design looking toward improvement in respect of one or more of the above features, and with the further view of simplifying the construction to the end that the manufacturing cost may be reduced. The latter is important since the devices are made to sell in a low price field to individual car owners.

The instant invention presents an exhaust deflector in which the design objectives above noted are thought to have been achieved in a greater degree than heretofore known.

The object of the present invention is to simplify the construction as well as the means and mode of attachment of such extensions to tail pipes, whereby such devices may not only be economically manufactured, but will be more efficient and satisfactory in use, adaptable to a wide variety of tail pipes, having relatively few parts and be unlikely to get out of repair.

A further object of the invention is to provide a tubular shell type deflector, attractive in appearance and wherein the utilitarian features are substantially concealed.

A further object is to provide a simplified means for attaching the deflector to the exhaust tail pipe, which in cooperation with the tubular shell produces a Venturi action aiding in scavenging the exhaust gases.

Another object of the invention is to reduce the cost of manufacture of the deflector by utilizing a fabricated construction wherein all the parts are relatively inexpensive metal stampings.

A further object of the invention is to provide a device possessing the advantageous structural features, the inherent meritorious characteristics and the mode of operation herein mentioned.

2

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

Referring to the accompanying drawing, 10 wherein is found the preferred but obviously not necessarily the only form of embodiment of the invention,

Fig. 1 is a perspective view of an exhaust deflector embodying the present invention;

Fig. 2 is an end elevation of the exhaust deflector.

Fig. 3 is a view of the exhaust deflector in side elevation; and

Fig. 4 is a view in longitudinal section taken 20 along the line 4—4 of Fig. 3.

Like parts are indicated by similar characters of reference throughout the several views.

Referring to the drawings, the illustrated embodiment of the invention comprises a generally tubular shell 10 made up of mating sections 11 and 12 having a semi-tubular shape viewed in cross-section. The longitudinal edges of the respective sections 11 and 12 are turned outward to define flanges 13 and 14. The sections 11 and 12 are arranged with their respective flanges 13 and 14 in closely adjacent relation, in which position the parts are held by spaced rivets 15 and 16 passed through the flanges. The adjacent longitudinal edges of the sections 11 and 12 accordingly are in registry and in substantially contacting relationship so as to produce the tubular shell 10.

As best seen in Fig. 3, the sections 11 and 12 making up the shell 10 are formed with opposed 40 tapers giving to the shell 10 a flared appearance at the opposite ends thereof. Thus, the shell has a constricted neck portion 17 defining a place or area of minimum diameter. From the area 17 the shell flares outwardly in either direction to 45 areas of maximum diameter at the respective outer ends. The constricted portion or area 17 is offset from the center of the shell, being relatively closer to the inner or attachment end of the shell. The taper extending toward the outer 50 end of the shell accordingly is of greater length

than the taper extending toward the inner end thereof.

Disposed in concentric spaced relation within the inner end of the shell 10 is an attachment collar 18. The collar 18 comprises mating sections 19 and 21 having respective side flanges 22 and 23, the sections being similarly shaped. The sections 19 and 21 are so assembled that the flanges 22 and 23 are in complementary opposed relation. At their outer ends they have a triangular formation and inward of the triangular formation have respective semi-cylindrical extensions 24 and 25.

The attachment collar 18 is arranged in the shell 10 with its respective sections 19 and 21 parallel to the sections 11 and 12 of the shell. At the inner end of each collar section 19 and 21 are oppositely disposed projections 26 and 27 received between the flanges 13 and 14 of the shell section 11 and 12, and clamped therebetween by the rivets 16 which pass through the projections on the attachment collar as well as through the flanges 13 and 14 of the shell. The clamping pressure applied at the inner ends of the collar sections by the rivets 16 tend to separate the sections at their outer ends which project slightly beyond the inner end of the shell 10.

Aligned openings are provided in the outer ends of the flanges 22 and 23 through which attachment bolts 28 extend into engagement with screw clips 29 embracing each flange 23. Adjustment of the bolts 28 causes the collar sections 19 and 21 to move toward or away from each other so as to accommodate the collar 18 to various tail pipes which are removably dumped therebetween. The extension 10 is thereby adjustably secured upon the terminal of an automobile tail pipe.

The clamp sections 19 and 21 are of semi-resilient material, the inner triangular ends thereof being so formed that they will afford a sliding frictional grip upon any tail pipe inserted therethrough by the mounting of the extension upon such pipe. Contraction of the outer or rearmost ends of the sections upon the pipe by adjustment of the bolts 28 thereby compresses the collar 18 into tight frictional engagement with the pipe adjacent the end thereof in substantial alignment with the projections 26-27, while the rearmost end of the collar is positively engaged with the tail pipe under influence of the bolts 28.

The semi-cylindrical portions 24 and 25 on the collar sections 19 and 21 cooperate to define a cylindrical extension projecting inwardly within the shell 10 through and beyond the constricted necked portion 17 thereof. There is thus provided between the cylindrical extension of collar 18 and shell 10 an annular Venturi chamber 31, tapering from a maximum width at the inner end of the shell to a minimum width at the constricted neck 17.

Upon forward motion of the vehicle, air passing alongside the tail pipe enters the chamber 31 and after passing the restricted neck portion 17 expands into the larger area of the shell outward of the necked portion, thereby inducing a more rapid and thorough evacuation of gases from the tail pipe under influence of the suction created by the Venturi effect of the extension. It will be understood that the collar 18 is clamped directly on the tail pipe and the exhaust gases are discharged therethrough toward the outer end of the shell 10.

At the front end of the tubular shell 10 is a pair of transverse ribs 32 and 33, superimposed one

upon another. Intermediate their ends, the ribs 32 and 33 are formed to an arcuate shape defining in conjunction with one another, an opening 34. The arcuate portions of the ribs 32 and 33 are formed with opposed tapers whereby the opening 34 assumes the appearance of a Venturi tube. The opposite ends of the ribs 32 and 33 are received between the flanges 13 and 14 of the shell at the location of the rivets 15 which are passed therethrough.

It will be noted that the deflector is a fabricated or assembled device, all the parts of which may be made of sheet metal stampings or the like. The three principal elements thereof, the shell 10, the collar 18, and Venturi tube 34, are of two-part sheet metal construction, all held together by only two sets of rivets 15 and 16. The attachment collar 18 and its associated parts are substantially concealed within the shell 10, which because of its curvature presents a pleasing streamlined appearance. The exterior of the shell may be chrome plated, and as shown the flanges 13 and 14 may be formed with opposed tapers corresponding to the shape of the shell to add to its attractiveness and to insure long wear.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

- An exhaust deflector, including a pair of semi-tubular shell elements flaring in opposite directions from a constricted neck portion intermediate their ends, complementary flanges along the longitudinal edges of said elements, said elements being arranged with said flanges in mating relation to define a tubular shell having an area of minimum diameter intermediate its ends and flaring outward thereof in both directions to areas of maximum diameter at the ends thereof, means holding said flanges in mating relation, an attachment collar adjacent one end of the tubular shell and surrounded thereby, said collar comprising two mating semi-cylindrical members the edges of which are out of contact through at least a part of their length, the cylindrical area of said collar extending in spaced concentric relation to said shell through and beyond the area of minimum diameter of said tubular shell, lateral ears on said collar elements adjacent their inner ends received between the flanges of said shell and connected thereto by the means holding said flanges in mated relation, and adjustment means passed transversely through said collar elements at their outer ends for effecting relative radial adjustment thereof.

- An exhaust deflector of the type wherein a deflector shell is detachably engageable with an exhaust pipe, comprising an expandable and contractible attachment member attached to and arranged within one end of the shell and connectable to the exhaust pipe, said attachment

member comprising two mating semi-cylindrical members the edges of which are out of contact, each semi-cylindrical member having ears at one end attached to the shell and clamping means at the other end for engaging the end of the exhaust pipe.
